UNITED STATES PATENT OFFICE

2,336,103

PIN

Madge Sanford Lane, Chicago, Ill.

Application November 21, 1941, Serial No. 419,921

1 Claim. (Cl. 24—155)

This invention relates to pins of a type adapted for wide use. It is the object of the invention to provide an improved form of pin adapted particularly for holding a bouquet or the like in position on a dress or a coat so as to be secured firmly while at the same time being capable of being quickly and easily removed when desired.

In the preferred arrangement of parts, two end members which ordinarily are in the form of ornaments are employed, one of said end members being provided with a pin arranged to extend readily into a socket in the other end member, said members being yieldingly connected together by a novel arrangement of parts by which the pin is normally held releasably from disengagement from the socket. It is the principal object of the invention to provide an arrangement and construction which can be produced and assembled very easily and quickly and which will be effective for its various purposes.

It is another object of the invention to improve devices of this type in sundry details hereinafter pointed out. The preferred means by which the several objects have been attained are illustrated in the accompanying drawing, in which—

Fig. 1 is a face view of my improved pin;

Fig. 2 is a view of a blank from which one of the end members of the pin is formed;

Fig. 3 is a side edge view of one of the end members of my improved arrangement with the pin broken away;

Fig. 4 is a rear face view of the parts shown in Fig. 1;

Fig. 5 is an edge view of the device shown partly in section;

Fig. 6 is a view similar to Fig. 1 but showing a modified form of end member; and

Fig. 7 is a back face view of the device as shown in Fig. 6.

Referring now to Figs. 1 to 5 of the drawing, in which corresponding parts are indicated by the same reference characters, 10 and 11 indicate the end members of my improved pin which in the arrangement shown are in the form of castings each comprising two plate portions 12 and 13 integrally connected together. The plates 12 and 13 are cast flat in the form shown in Fig. 2. After their formation in blank form, the plate portion 13 is bent backwardly along the face of the plate portion 12 into substantially the arrangement as shown in Fig. 3 so as to give the two plates the form of a hook.

As is best shown in Figs. 4 and 5, the end member 10 at the left in Fig. 4 is provided with a pin

14 projecting longitudinally from the member at the point where the two plate portions are integrally connected, the end member being cast in position about the pin so as to have a strong rigid connection therewith. For receiving the pin 14, and swivelling thereon to dispose the end members approximately co-planar, the end member 11 is provided with a socket 15, as is clearly shown in said Figs. 4 and 5.

10 In the arrangement shown, the end members 10 and 11 are connected together by a rubber band 16 which engages the hooks of the end members at their bight portions which are relatively wide so as to hold the end members in close 15 proximity to each other and cause them to swivel relatively to each other into the approximately co-planar relation mentioned. The arrangement is such that the rubber band normally holds the pin 14 releasably in engagement with the socket 15 so as to prevent movement of the pin out of the socket except as the end members are moved longitudinally away from each other against the action of the resilient band.

By my improved arrangement, I have evolved a 25 construction which can be very quickly and easily provided and can be very easily assembled into its final form. The plates 12 and 13 are preferably in the form of leaves so as to make the pin very appropriate for use for holding a bouquet 30 in position.

In the arrangement shown in Figs. 6 and 7, end members 17 and 18 are employed, each comprising a plate 19 with a lug 20 formed integrally therewith and extending backwardly along the face of the plate. The end member 17 is provided with a pin 21 which is secured in the lug 20, such pin 21 being arranged to extend into a socket 22 formed in the lug 20 of the end member 18. The end members are connected together in this arrangement by means of a rubber band 40 16 just as are the end members 10 and 11 of the arrangement first described.

While I prefer to employ the form of pin as shown in the drawing and as above described, it 45 is to be understood that the invention is not limited to the construction shown except so far as the claims may be so limited, since changes might well be made in the form and arrangement of the parts without departing from my invention.

I claim:

In a device of the type described, the combination of two end members each comprising a body portion in the form of a plate and a second plate portion extending backwardly along the face of

the body portion so as to form a hook therewith having a relatively wide bight portion at their junction, a pin fixedly connected to one of said end members releasably and swivelly engaging a socket provided by the other member, and resilient connecting means in the form of an endless loop engaging said relatively wide bight por-

tions providing laterally spaced apart portions parallel to each other and to said pin yieldingly to hold said pin when engaged with said socket from moving out of engagement therewith and to hold said end members approximately coplanar.

MADGE SANFORD LANE.
